UNITED STATES PATENT OFFICE.

JOSEPH LOCKE, OF TOLEDO, OHIO, ASSIGNOR TO THE W. L. LIBBEY & SON COMPANY, OF SAME PLACE.

DESIGN FOR A NAPKIN-RING.

SPECIFICATION forming part of Design No. 19,461, dated December 3, 1889.

Application filed October 7, 1889. Serial No. 326,284. Term of patent 3½ years.

To all whom it may concern:

Be it known that I, JOSEPH LOCKE, a citizen of the United States, and a resident of Toledo, in the county of Lucas and State of Ohio, have 5 invented and produced a new and original Design for Napkin-Rings; and I do hereby declare that the following is a full, clear, and exact description of the invention, which will enable others skilled in the art to which it 10 appertains to make and use the same, reference being had to the accompanying drawings, and to the letters of reference marked thereon, which form part of this specification.

The class to which this design relates is 15 that of napkin-rings.

Figure 1 is a bottom view of the ring. Fig. 2 is side elevation of the same with a napkin held therein; and Fig. 3 is a longitudinal vertical section centrally of the ring.

20 The leading features of my design are a hollow sphere having a tripartite truncation, whereby there are formed three plane surfaces, one of which forms a base, while the oppositely-truncated sides form coincident 25 openings, through which the napkin is passed.

A designates a hollow sphere having portions thereof cut away upon three sides, whereby there are formed three plane surfaces B, one of the surfaces serving as a base, and the opposite cut-away portions, being in horizontal alignment, form an opening, through which the napkin C is passed.

A napkin-ring embodying my design presents a very ornamental appearance, and the remaining surface of the sphere affords a 35 ground upon which I place any desired embellishment.

What I claim is—

The design for a napkin-ring herein described and shown, consisting of a hollow 40 sphere having a tripartite truncation, as set forth.

In testimony that I claim the foregoing as my own I hereby affix my signature in presence of two witnesses.

JOSEPH LOCKE.
